(57) **CLAIM**

The ornamental design for an LED flashing light for gloves, as shown and described.

DESCRIPTION

FIG. 1 is a perspective view of an LED flashing light for gloves showing my new design.

FIG. 2 is a front view of an LED flashing light for gloves.

FIG. 3 is a rear view of an LED flashing light for gloves.

FIG. 4 is a left side view of an LED flashing light for gloves.

FIG. 5 is a right side view of an LED flashing light for gloves.

FIG. 6 is a top view of an LED flashing light for gloves.

FIG. 7 is a bottom view of an LED flashing light for gloves; and,

FIG. 8 is another perspective view showing the LED flashing light for gloves mounted on a glove.

The broken lines shown in FIG. 7 depict portions of the LED flashing light for gloves that form no part of the claimed design.

The broken lines shown in FIG. 8 depict environment only and form no part of the claimed design.

1 Claim, 8 Drawing Sheets
